UNITED STATES PATENT OFFICE.

HARRY D. CLINTON, OF JOHNSON CITY, NEW YORK.

JACK SPOOL.

Application filed June 19, 1925. Serial No. 38,351.

To all whom it may concern:

Be it known that I, HARRY D. CLINTON, a citizen of the United States, residing at Johnson City, in the county of Broome and State of New York, have invented certain new and useful Improvements in Jack Spools; and I do hereby declare the following to be a full, clear, and exact description of the invention, such as will enable others skilled in the art to which it appertains to make and use the same.

This invention relates to jack spools such as are used especially by the woolen and worsted manufacturers and in the knitting trade, in the manufacture of yarn, and also to ship yarn from one branch to another or from one mill to another; such spools being made of different lengths varying from 24 to 72 inches between the heads, and the heads varying in diameter from 6 to 12 inches.

The spools are provided with gudgeon pins which project from opposite ends thereof. Ordinarily the gudgeon is secured to the end of a wooden barrel by simply boring a hole in the end of the barrel and a transverse hole or slot to receive a nut which is screwed on a threaded part of the gudgeon which is inserted in the first mentioned hole. Such a construction is defective inasmuch as the gudgeon is constantly becoming loose and it is a difficult matter to screw the nut on securely on the inside of the barrel and when the gudgeon becomes loose it causes a great deal of trouble, as the head is apt to come off and permit the yarn to slough off over the end of the spool, usually causing considerable loss, and it is desirable that the head should be detachable, because frequently the head or barrel breaks, in which case a new head can be used with the old barrel or a new barrel with an old head, but even though the head is detachable it should also be possible to apply the head so that it cannot work loose or come off otherwise than by actual intent.

The objects of my invention are to overcome the difficulties hereinbefore mentioned incident to the use of jack spools as heretofore constructed, and to provide a jack spool with detachable heads and gudgeons firmly secured together so that they cannot become loose or detached in actual use but may be easily separated when it is desired to remove the head in case of breakage or for other cause.

The invention will first be hereinafter more particularly described, with reference to the accompanying drawings, which are to be taken as a part of this specification, and then pointed out in the claims at the end of the description.

In said drawings, Fig. 1 is a plan view of a jack spool constructed in accordance with my invention;

Fig. 2 is an end view of the same; 65

Fig. 3 is a vertical sectional view of a broken away end portion of the spool shown in Figs. 1 and 2; and

Fig. 4 is a perspective view of the several parts shown in Figs. 1 to 3 in position for 70 assembling and securing said parts together.

Referring to said drawings, in which the same reference letters are used to denote corresponding parts in different views, the letter A denotes a wooden barrel, which may be of tubular form or provided with a socket in each end thereof, to receive a bushing B, preferably of wood, inserted in the opening or socket at one end of the barrel and held therein by glue or other adhesive substance. The bushing B has an axial opening b therethrough to receive the bolt C carrying the gudgeon pin and an oblong recess b¹ extending transversely of 85 said opening to receive an oblong head c on the inner end of said bolt, to prevent the bolt from turning. The bolt has a threaded portion intermediate its ends on which is screwed a nut D, whereby the head of the 90 bolt may be drawn tightly into said recess, thereby firmly securing the bolt with the gudgeon pin thereon to said bushing; the bolt being inserted and secured to the bushing before the bushing is inserted and glued 95 or otherwise secured within the barrel. A

second nut E of polygonal form, preferably square, is then screwed on the threaded portion of the bolt C and a spool head F, preferably of hard fibre, having a square or 100 polygonal opening therein, is placed on the bolt with said second nut fitting snugly within the opening through the head, so that said second nut and the head will rotate together; rotation of one independently of the other being prevented when the nut is screwed up by rotation of the head so as to firmly press the head against the end of the spool barrel. Thereupon a jam nut 105 or metal washer G having a peripheral por- 110

tion g bearing upon the outer side of the head and a central boss or protuberance g^1 bearing upon said second nut, is screwed on the threaded part of the bolt for securing the 5 several parts together, said head and washer being provided with oppositely disposed holes therein, as shown, for applying a spanner wrench thereto, and when the head is rotated the nut E will turn therewith and 10 jam the head tightly against the end of the barrel, whereupon the washer may be screwed up against the head and nut so as to jam the head more tightly against the end of the barrel, and jam the washer tightly 15 against the head and second nut, the washer and second nut acting on the principle of two jam nuts. The assembled parts are thus firmly secured together and held in place so as to prevent the head or the gudgeon 20 from turning or becoming loose or the head from coming off, until sufficient force is applied to unscrew the washer by the application of a spanner wrench for that purpose, and the fibre head will be firmly held be- 25 tween the end of the spool barrel and the nut E with no tendency to become loose until the washer is unscrewed, whereupon the head may be easily taken off of the barrel by means of a spanner wrench applied thereto.

Preferably a steel ferrule or sleeve H is secured on a reduced end portion of the barrel so as to abut against the fibre head and prevent wear on the ends of the barrel and 35 also strengthen the entire construction. Such ferrule however may be dispensed with, especially if the barrel is made of harder material than wood.

Having thus described my invention, what 40 I claim as new and desire to secure by Letters Patent of the United States is:

1. The combination, in a device of the character described, of a barrel having a bushing inserted in one end thereof, said bushing having a longitudinal opening therethrough and a recess at the inner end thereof extending across said opening, a bolt inserted in said opening having an intermediate threaded portion and an oblong 45 head on its inner end fitting in said recess, the free end of said bolt projecting beyond the outer end of said bushing, a nut screwed on said bolt so as to draw said head into said recess, a second nut screwed on said bolt adjacent the first named nut, a disk-like device screwed on said bolt adjacent said second nut, and a spool-head interposed between said second nut and said device, said head having a central polygonal opening 50 therein fitting over said second nut so as to cause the nut and head to rotate together; said device having a centrally disposed part adapted to contact with said second nut and a peripheral portion adapted to contact 55 with the outer side of said head for clamp-

ing the latter tightly against the end of said barrel.

2. A device of the character described comprising a tubular barrel having a bushing inserted in each end thereof, said bushing having a longitudinal opening therethrough and a recess extending across said opening at the inner end thereof, a bolt inserted in said opening having an oblong head on its inner end fitting in said recess and an intermediate threaded portion and a gudgeon pin on its free end projecting beyond the end of the barrel, a jam nut screwed on said bolt adapted to draw said head into said recess, a second nut of polygonal form screwed on said bolt adjacent the first named nut, a spool-head having a central polygonal opening therein fitting over said second nut, and a washer-like device or jam nut screwed on said bolt and having a centrally disposed boss adapted to contact with said second nut and a peripheral portion adapted to contact with the outer side of said spool-head, whereby said head may be jammed tightly against the end of the spool barrel and firmly held in place.

3. The combination, in a device of the character described, of a bushing inserted and secured in the end of a barrel, said bushing having an opening therethrough and a bolt inserted in said opening and carrying a gudgeon, said bolt being threaded between its ends and having a head bearing against one end of said bushing, and a nut screwed thereon and bearing against the other end of said bushing, and means to prevent said bolt from turning, a clamping device screwed on said bolt, and a spool-head interposed between said device and the end of the barrel, said head having a central opening therein fitting over a nut screwed on said bolt, and said clamping device having a bearing against said head and the last named nut.

4. A jack spool comprising a wooden barrel having wooden bushings inserted and secured in opposite ends thereof, each of said bushings having an axial opening therethrough and a recess in its inner end adapted to receive the head of a bolt and prevent it from turning, a bolt inserted in said opening having at one end a head non-rotatively fitted in said recess and a gudgeon projecting from the other end thereof beyond said bushing; the intermediate portion of said bolt being threaded and having a nut screwed thereon and pressing against the end of the bushing so as to draw said head into said recess, a second nut of polygonal form screwed on said bolt, a spool-head having a central polygonal opening therein fitting over said second nut, and a washer-like device screwed on said bolt and bearing against said spool-head so as to press the latter tightly against the end of said barrel.

and having a jam nut action against said second nut so as to lock the same and firmly secure the several parts together.

5. A jack spool comprising a wooden barrel having wooden bushing inserted and secured in opposite ends thereof, each of said bushings having an axial opening therethrough and a recess in its inner end adapted to receive the head of a bolt and prevent it from turning, a bolt inserted in said opening having at one end a head non-rotatively fitted in said recess and a gudgeon projecting from the other end thereof beyond said bushing; the intermediate portion of said 10 bolt being threaded and having a nut screwed thereon and pressing against the end of the bushing so as to draw said head into said recess, a second nut of polygonal form screwed on said bolt, a barrel-head 15 having a central polygonal opening therein fitting over said second nut, and a washer-like device screwed on said bolt and bearing against said spool-head so as to press the latter tightly against the end of said 20 barrel and having a jam nut action against said second nut so as to lock the same and firmly secure the several parts together;

said spool-head and washer-like device having holes therein for applying a spanner wrench thereto.

6. In a jack spool, a wooden barrel having a wooden bushing inserted and secured in one end thereof, said bushing having an axial opening therethrough and a rectangular recess in its inner end, a bolt inserted in 30 said opening having a rectangular head at one end secured in said recess, its other end being plain and projecting beyond the outer end of said bushing, the intermediate portion of said bolt being threaded and having two 35 nuts screwed thereon, one nut serving to draw said head into said recess and the other nut fitting within a central hole in a spool-head for screwing the latter on said bolt tightly against the end of said barrel, 40 and a metallic washer screwed on said bolt and bearing upon said spool-head and the nut within said central hole so as to press the spool-head tightly against the end of the 45 spool and lock the last named nut, thus 50 firmly securing the several parts together.

In testimony whereof I affix my signature.

HARRY D. CLINTON.
